UNITED STATES PATENT OFFICE.

CHARLES LE G. FORTESCUE, OF PITTSBURGH, PENNSYLVANIA, ASSIGNOR TO WESTINGHOUSE ELECTRIC & MANUFACTURING COMPANY, A CORPORATION OF PENNSYLVANIA.

MODULATING SYSTEM.

Application filed October 25, 1921. Serial No. 510,337.

My invention relates to wireless telegraphy and more particularly to means for controlling the power output of a transmitting antenna system.

5 One of the objects of my invention is to neutralize the coupling between the supply circuit and the antenna circuit to prevent the transfer of energy therebetween.

10 A further object is to avoid all arcing between the contact points of the sending key.

15 A still further object is to provide means for quickly absorbing the residual energy stored in the radiating circuit by causing the residual oscillations to set up a branch-to-branch current in a multiple-branch antenna.

20 My invention consists in the methods and apparatus described in the following detailed description and illustrated in the accompanying drawing, wherein:

Figure 1 is a diagrammatic view of an embodiment of my invention employing a common form of antenna, and

25 Fig. 2 is a similar view of a modification employing a multiple-branch antenna in accordance with my invention.

In the system shown in Fig. 1, I provide a high-frequency source 3, which is connected to the primary coil 4 of a coupling transformer having a loosely coupled secondary coil 5, which is included in an antenna circuit 6. Connected in shunt relation to the primary coil 4 is a closely coupled, 35 oppositely wound tertiary coil 7 including in circuit therewith a controlling key 8 and a resistor 9.

By virtue of the arrangement just described, power is supplied to the antenna circuit 6 when the key 8 is open. When the key is closed, current flows through the primary and tertiary coils in opposite directions, thereby substantially neutralizing the coupling of these coils to the secondary coil 5, and the energy of the source 3 is absorbed by the resistor 9 which may be of such value as to maintain a substantially constant load upon the source. When the key is again opened, there is no tendency to arc, as the 50 secondary circuit begins at once to deprive the tertiary circuit of its energy.

Under certain circumstances, it may be found advantageous to include a capacitive reactance in the primary or tertiary circuit

in order to neutralize the leakage inductance 55 of the system, as indicated at 10 and 11 in Fig. 1.

In Fig. 2, I have shown a similar system, in which the usual antenna circuit 6 has been replaced by a multiple-branch antenna 60 circuit 12 including two adjacent antennæ 13 and 14. The antennæ 13 and 14 are shown as comprising alternate wires of a single antenna construction 15, said alternate wires being connected, in two groups, to antenna leads 16 and 17, respectively. Connected to the ends of the antenna leads is a balancing coil 18 having its mid-point connected to ground through the secondary coupling coil 5.

The antenna leads 16 and 17 may include tuning coils 19 and 20, respectively, whereby the antennæ may be tuned to the frequency of the source 3. Means are provided, also, as by making the tuning coil 20 larger than 75 the tuning coil 19 and inserting a compensating condenser 21, whereby the time constant of one of the antennæ is made larger than that of the other for a purpose which will appear hereinafter.

80 In operation, the switch 8 is manipulated as in the system shown in Fig. 1. During transmission of signal impulses, the current divides equally between the two halves of the balancing coil 18, and energy is transmitted from the two antennæ operating in unison. When the energy of the source is diverted from the secondary coupling coil 5, the residual stored energy in the antenna circuits causes the oscillations to continue 90 for a few cycles, dependent upon the time constant of the system.

95 In order to increase the rate at which the oscillations will decrease after the interruption of the source of supply to the antennæ, the system is so designed that one antenna has a larger time constant than the other, whereby circulating currents are established in the circuit including the capacitance between the two antennæ, the tuning coil 19, the balancing coil 18, the tuning coil 20 and the condenser 21. The 100 circuit just mentioned is designed to have a natural period corresponding to the frequency of the source 3, whereby local oscillations will be set up therein which will quickly absorb the stored energy without causing any sparking at the switch 8.

While I have described certain forms of my invention in detail, and while I have pointed out certain of the most obvious principles and purposes thereof, I do not intend that the language employed in the following claims shall be limited to the precise features described, but I intend that the claims shall be construed to cover all combinations which are fairly included in the language thereof, when read in view of the prior art regardless of the details and functions mentioned in the description or illustrated in the drawing.

I claim as my invention:

1. In combination with a transformer having an auxiliary demagnetizing winding, an antenna system, said transformer constituting a loose coupling for supplying energy to said antenna, a load for said auxiliary winding, and means for transferring energy from said antenna system to said load by demagnetizing said driver transformer.

2. A coupling system comprising a primary induction coil, a secondary induction coil, a tertiary induction coil, the primary and tertiary coils being relatively-tightly coupled and the secondary coil being relatively-loosely coupled to the primary coil, the tertiary coil being wound to oppose the effect of the primary coil on the secondary coil, means for controlling the flow of current through the tertiary coil, and a condensive reactor in circuit with the tertiary coil to resonate with the leakage inductance of the system.

3. A coupling system comprising a primary inductance coil, a secondary induction coil, a tertiary induction coil, the primary and tertiary coils being relatively-tightly coupled and the secondary coil being relatively-loosely coupled to said primary coil, the tertiary coil being wound to oppose the effect of the primary coil on the secondary coil, means for controlling the flow of current through the tertiary coil, and a resistance device and a capacitance device in circuit with the tertiary coil, said capacitance device being of such size as to resonate with the leakage inductance of the system.

4. A sending system comprising a multiple-branch radiating circuit including an antenna, means for supplying current to the multiple-branch circuit, and means for modulating said current, said radiating circuit including means for causing residual antenna-charges to set up a branch-to-branch current.

5. A sending system comprising a source of high-frequency oscillations, a multiple-branch antenna coupled thereto, an inductance device in each branch, and means for controlling the current supplied to the multiple antenna from the high-frequency source, said antenna including means

whereby a branch-to-branch current is set up when the energy supplied to said antenna by the high-frequency source is reduced.

6. A sending system comprising a continuous-wave source of high-frequency oscillations, a multiple-branch antenna coupled thereto, means for controlling the current supplied to the multiple-branch antenna, and means for causing residual charges to set up current-flow in a branch-to-branch circuit.

7. A sending system comprising a continuous-wave source of high frequency oscillations, a primary induction coil energized therefrom, a secondary induction coil relatively-loosely coupled to said primary coil, a tertiary induction coil relatively-tightly coupled to the primary coil, the tertiary coil being so wound as to oppose the effect of the primary coil on the secondary coil, and a multiple-branch antenna energized from said secondary coil and including a resonant branch-to-branch circuit.

8. The combination with a pair of antenna-to-ground circuits having different time constants, of means for energizing said circuits from a common source, and means for providing a tuned antenna-to-antenna circuit for increasing the damping of the circuits with respect to said common energizing means.

9. A wireless transmitting system including two antennæ, antenna-leads connected thereto, an impedance device joining said leads, a ground connection from an intermediate point of said impedance device, means associated with said ground connection for energizing said antennæ for radiation in unison, means for tuning the antenna-to-ground and antenna-to-antenna circuits, and means for causing one antenna-to-ground circuit to have a different time constant than the other.

10. The combination with a pair of antennæ and a source of high-frequency energy, of means for causing said energy to divide substantially equally between said antennæ during transmission of signal impulses, means for diverting the energy of said source from said antennæ, and means for causing a time lag of the residual oscillations in one antennæ with respect to those in the other, and means for providing an antenna-to-antenna circuit effective to circulate local currents resulting from said time lag.

11. A wireless signaling system including an antenna-to-ground circuit and a loop circuit associated therewith, said loop circuit including two branches tuned to the signaling frequency and having different time constants, said loop circuit, as a whole, being also tuned to the signaling frequency.

12. In a radio-transmitting system, the

combination with a continuous-wave source, of a pair of oppositely-wound and inductively coupled coils connected thereto, means for varying the energy in one of said coils whereby the magnetic flux is correspondingly varied, an antenna system coupled to said coils, and means included in said antenna system and providing a local circuit tuned to the frequency of said source and so disposed as to carry circulating currents only upon a change in the amount of energy supplied to said antenna system.

13. In a radio-transmitting system, the combination with a continuous-wave source, of an antenna system coupled thereto, means for causing a change in the amount of energy supplied to said antenna system, and means included in said antenna system and providing a local circuit tuned to the frequency of said source and so disposed as to carry circulating currents only upon a

change in the amount of energy supplied to said antenna system.

14. The combination with a high-frequency supply circuit, of a pair of shunt circuits including oppositely-wound transformer coils connected to said supply circuit, condensive reactance means in one or more of said circuits for neutralizing the inductive reactance therein, a tuned secondary circuit in inductive relation to said coils, and means for varying the energy supplied to said secondary circuit, said means including means for varying the relative magnetizing effects of said coils and means for maintaining a substantially constant total load on said supply circuit.

In testimony whereof, I have hereunto subscribed my name this 18th day of October, 1921.

CHARLES LE G. FORTESCUE.
